TUMBLER OR SIMILAR ARTICLE

James Lloyd Thrush, Lancaster, Ohio, assignor to Anchor Hocking Corporation, Lancaster, Ohio, a corporation of Delaware

Filed Jan. 13, 1970, Ser. No. 20,909

Term of patent 14 years

Int. Cl. D7—01

U.S. Cl. D36—8

FIG. 1 is a side elevational view of a tumbler or similar article showing my new design;

FIG. 2 is a top plan view thereof;

FIG. 3 is a sectional view taken along line 3—3 of FIG. 1;

FIG. 4 is a sectional view taken along line 4—4 of FIG. 1; and

FIG. 5 is a fragmentary developed plan view of the ornamentation.

I claim:

The ornamental design for a tumbler or similar article, substantially as shown.
